CARPET SAMPLE DISPLAY STAND

Fred Howard, New York, N.Y., assignor to Howard Displays, Inc., New York, N.Y.

Filed Feb. 5, 1973, Ser. No. 329,552

Term of patent 14 years

Int. Cl. D6—04

U.S. Cl. D6—186

FIG. 1 is a left perspective view of a carpet sample display stand showing my new design;

FIG. 2 is a right rear perspective view thereof;

FIG. 3 is a right perspective view thereof; and

FIG. 4 is a left perspective view of a carpet sample display stand showing a modified form of my new design with transparent side panels and a mirrored top panel.

I claim:

The ornamental design for a carpet sample display stand, as shown and described.
